UNITED STATES PATENT OFFICE.

THOMAS R. PRINCE, OF ST. GEORGES, NEWFOUNDLAND.

ROTARY ENGINE.

Application filed October 25, 1919, Serial No. 333,150. Renewed January 11, 1924.

This invention relates to steam engines, and more especially to those of the rotary type having a steam operated swinging abutment; and the broad object of the invention 5 is to improve the shape of the abutment and particularly the valve end thereof and the shape of the coacting parts of the cylinder and rotor so as to reduce to a minimum and practically do away with noise, jar, and loss 10 of the fluid agent and therefore of power. Said agent may be steam or compressed air, in which event advantage is taken of expansion as well as impact, or it may be gas, water, or possibly an explosive mixture in 15 which last case means must be provided to ignite the fluid at the proper moment and simultaneously to cut off the intake so that the force of the explosion will be directed forward only. I reserve the broadest latitude with respect to the fluid agent used, although I will describe my engine as driven by steam.

The invention as disclosed below and shown in the accompanying drawings is applied to a single cylinder having two intakes 25 with their swinging abutments and two exhausts, and a single concentric rotor having two wings; but it will be clear without further description and illustration that the invention is not limited in these respects.

With this understanding the following specification sets forth a successful construction of this improved engine, reference being made to the drawings in which:

35 Figure 1 is a vertical section through the cylinder and an elevation of its abutments and its rotor, showing the valves closed and the wings as just about to pass and permit them to open. I have made use of one side 40 of this view to employ reference numerals, while the names of certain parts have been placed on the other side in order that the drawings may be more easily read.

Figure 2 is a similar view of one-half of 45 Figure 1 showing the wing in full lines as having progressed until the corner of its face is about under the midlength of its rocker, and in dotted lines as having progressed to a point where the rocker has dropped onto the angle at the beginning of 50 the cam and the valve is about to open.

Figure 3 is a similar view showing the wing in full lines as having progressed to

a point where the rocker is traveling down the receding face of the cam and the valve 55 is partly open, and showing the parts in dotted lines with the valve wide open.

The well known elements of a rotary engine of this character are indicated broadly in the drawings by reference letters. Mounted on a base B is a cylinder C whose bore is struck on a true circle and whose shell in the present case contains two diametrically disposed inlets or intake passages I, each controlled by an abutment A mounted at 60 one end on a pivot and having a valve at its other end, and the shell of the casing also has two exhaust ports X whereof each is a considerable distance in advance of its intake so as to get the full force of expansion as well as the force of impact in case 65 steam is the fluid agent. Mounted on a shaft S extending transversely through the exact axis of the bore of the cylinder is the rotor R, herein shown as having two diametrically opposite and identical portions where the periphery of the rotor fits as closely as possible within the bore of the cylinder. Although packing will be used to effect a close 70 fit between parts and means will be provided for suitable lubrication, I have not considered these details necessary to the present case. The parts should be of the proper materials to resist wear as long as possible, and their proportions will depend 75 upon the size of the engine being built and other conditions such as the character of the motive fluid employed. I would suggest, however, that it might be well to make each abutment of a length over all which is about 80 one-fourth the diameter of the rotor, and its width about one-twelfth such diameter. Also the steam space where it is widest should be about one-twelfth said diameter to produce the greatest effectiveness in the unit 85 illustrated. The rear end 1 of the abutment A is struck on a true arc around the axis of the pivot 8 and fits closely within a similarly shaped socket 2 in the wall of the casing at one side of the intake I; the back 90 3 of the abutment is preferably flat and lies squarely across the intake when closed; the opposite or inner edge 4 of the abutment is flat from its rear end 1 parallel with the back for quite a distance and is then rounded 95 or curved outward to constitute what I will

105

call a rocker 5, the same terminating at the tip 6 of the abutment remote from its pivot; and the valve 7 is formed by cutting off the end of the abutment from the tip to its back 6 on a line forming an obtuse angle with said back, possibly at an angle of about 135° . The wall of the casing around the mouth of the intake is recessed to form a chamber of such size as to fully receive the abutment 10 when the valve is closed. One end of this chamber is the socket 2 above referred to, the same communicating at the point 11 with the bore of the cylinder; from this end the chamber extends completely across 15 the intake; and the other end of the chamber is made up of a valve seat 17 standing on an angle to coincide with the working face of the valve 7, and a seat extension 15 struck on an arc around the pivot 8 from a point 16 where the extension unites with the seat to a point 14 where it unites with the bore, and in the movement of the abutment to open and close its valve, its tip 6 swings across the face of this extension. 20

23 The rotor R is shown herein as having two wings. Commencing at the point 20 the periphery 21 of the piston itself which coacts with the bore of the cylinder and is fitted closely therein as by means of inserted packing 22, extends back in the direction of rotation to the corner 23 of what might be called the wing 24. In rear of the latter is formed a pocket 25, composed preferably of a flat face 26 standing on a radius 30 of the rotor, a bottom 27, and an inclined back 28, the latter leading out to an angle 29 which marks the beginning of the steam space 30 and stands a shorter distance from the axis of the rotor than the corner 23; 40 or in other words, the pocket is deeper at its face 26 than at its back 28, and the relative position of the corner 23 and angle 29 is important for reasons set forth below.

45 The steam space 30 behind each wing is bounded on its outer side by the bore of the cylinder and its ends by the heads of said cylinder as will be clearly understood. Its inner side is bounded by a long cam formed by cutting away the periphery of the rotor, and this cam is made up of a receding face 31 leading from the angle 29 to a point 32 and preferably on a gentle curve slightly spiral to the axis, a concentric face 33 leading from the point 32 a 50 considerable distance rearward to the point 34 and struck on an arc which is concentric to the axis and opposite which face the steam space has its greatest width, and finally a rising face 35 which is herein shown as rising first on a tangent 36 from the point 34 to the point 37, then on a short curve 38, and finally on another tangent 39 to a point 40 where the steam space ends, this point being coincident with the 60 point 20 at the beginning of the periphery

of the other wing 24. Manifestly the length of this steam space and the shape of the various faces of the cam are matters which are subject to considerable variation, and doubtless will be regulated by experiment 70 in the evolution of a successful engine of this type. Obviously the space would have to be shortened if three wings were employed with two abutments. In that case, or in any case, the exact point where the 75 exhaust X opens into the steam space, its size and its direction and the question of whether it shall have a valve or not, are also matters which may be left to the builder. What might be called the essential features of construction are the shape of the valve seat and valve and the rocker or inner edge of the abutment, as well as the shape of the pocket and its walls and the receding face 31 of the cam. 80

85 With the parts standing as seen in Figure 1 and the rotor revolving in the direction of the arrow, the edge of the wing 24 is yet holding the valve 7 closely against its seat and the motive fluid within both 90 steam spaces 30 is flowing out the exhausts X. The rotor now moves to the position indicated in full lines in Figure 2, where the corner 23 has traveled perhaps half way along the rocker 5 so that the pressure on the back 3 of the abutment has moved the valve 7 from its seat 17 and its tip 6 has passed part way down the extension 15. Further progress of the rotor to the position dotted in this view permits further inward swinging of the abutment, the corner 23 passes the tip 6 and the heel of the rocker drops onto the angle 29. At this time the motive fluid begins to pass the tip 6 into the pocket 25. Further movement of the 95 rotor carries the angle 29 along under the rocker so that the latter rests on the receding face 31 of the cam as seen in full lines in Figure 3; and as this face travels 100 under the rocker the valve opens more and more as the abutment swings inward, and finally reaches its wide open position with the parts standing as seen in dotted lines in this view. Of course the rotor is revolving rapidly, but during the action described 105 the fluid is admitted more and more rapidly past the opening valve, and flows over the face 31 into the pocket 25 and directly 110 against the flat face 26 of the wing 24, thereby using the impact of the inrushing 115 fluid to revolve the rotor. The pressure of said fluid on the back 3 of the abutment merely bears its rocker downward onto the cam face, and the latter recedes from the angle 29 to the point 32 so as to permit 120 the abutment to yield to this pressure until its valve is wide open. Further movement of the rotor carries the concentric face 125 33 under the rocker and holds the latter with the valve wide open so that an ample 130

charge of motive fluid is admitted; and eventually the abutment is swung outward by the rising face 35 until the valve is fully closed by the periphery 21 of the succeeding wing.

Thus it will be seen that—without considering at all the question of expansion—the motive fluid is admitted at first slowly and then through a wide open valve at the 10 free end of a swinging abutment, the same being pivoted in such manner that when it swings it directs the fluid tangentially around the rotor and against the flat face of the piston wing 24. In other words, the 15 fact that the rear wall of the pocket is not as deep as its front wall and unites at 29 with a receding face 31 of the cam, serves two functions; first it affords a support for the rocker 5 when the corner 23 of the wing 20 releases it, and second it affords a channel into the pocket through which the motive fluid may flow, this channel growing wider as the valve opens while the rocker travels down the face 31 to the point 32. The back 25 3 of the abutment now stands oblique to the line of the inflowing motive fluid, and directs it along said channel into the pocket, which it continues to do until and unless it is cut off in case it is steam whose expansion it is de- 30 sired to use. The outward curve of the 10 rocker 5 not only coacts with the angle 29 to permit the abutment to swing inward by degrees, but it coacts with the specific cam faces on the rotor behind the pocket to per- 35 mit the abutment to swing yet further in- 40 ward until its valve 7 is wide open, then hold it there, and finally to close it—thereby pro- 45 ducing the greatest effectiveness. At no time 50 is there not a direct contact between either 55 the inner edge 4 or the rocker 5 of the abut- 60 ment on the one hand, and some point or an- 65 gle or face of the rotor on the other hand, and therefore the escape of live steam is re- 70 duced to a minimum and the bulk of it is 75 directed forward into the pocket 25 and di- 80 rectly against the face 26. Meanwhile the 85 dead steam within the space 30 is exhausting at X, and experience has proven that this 90 space where it is widest opposite the concen- 95 tric face of the cam accommodates the ex- 100 pansion so that there is little or no back pres- 105 sure imparting a drag on the rotor by chok- 110 ing the outlet.

What is claimed is:

1. In a rotary steam engine, the combina- 55 tion with a casing having diametrically op- 60 posite inlet ports and adjacent diametrically op- 65 posite exhaust ports, the inner end of each 70 inlet port being formed with a chamber hav- 75 ing a beveled seat in one wall, a swinging 80 valve pivotally supported in the opposite 85

wall of the chamber and having a beveled 90 end for seating on the said seat, and a rotor 95 consisting of an approximately cylindrical block having diametrically opposite motive 100 fluid receiving pockets in its periphery, the 105 forward wall of each pocket being radial 110 with respect to the axis of the rotor and the 115 rear wall at an obtuse angle to the bottom 120 of the pocket, the peripheral face having a 125 curved portion receding from the rear wall 130 of the pocket toward the said axis, a portion 135 concentric with and spaced from the casing 140 rearwardly of the said curved portion, a 145 straight portion extending rearwardly from 150 the concentric portion, and a curved portion 155 extending from the last-named portion to the 160 casing.

2. In a rotary steam engine, the combina- 165 tion of a casing having an inlet port and an 170 exhaust port, the inner end of the inlet port 175 being formed with a chamber having a bevel- 180 ed seat in one wall, a swinging valve pivot- 185 ally supported in the opposite wall of the 190 chamber and having a beveled end for seat- 195 ing on the said seat, and a rotor consisting 200 of an approximately cylindrical block hav- 205 ing a motive fluid receiving pocket in its pe- 210 riphery, the forward wall of the said pocket 215 being radial with respect to the axis of the 220 rotor and the rear wall at an obtuse angle 225 to the bottom of the pocket, the peripheral 230 face having a curved portion receding from 235 the rear wall of the pocket toward the said 240 axis, a portion concentric with and spaced 245 from the casing rearwardly of the said 250 curved portion, a straight portion extending 255 rearwardly from the concentric portion, and 260 a curved portion extending from the last- 265 named portion to the casing.

3. In a rotary engine, the combination 270 with a casing having diametrically opposite 275 inlet ports and adjacent diametrically op- 280 posite exhaust ports, the inner end of each 285 inlet port being formed with a chamber hav- 290 ing a beveled seat in one wall, a swinging 295 valve pivotally supported in the opposite 300 wall of the chamber and having a beveled 305 end for seating on the said seat, and a 310 rotor consisting of an approximately cylin- 315 drical block having its peripheral face pro- 320 vided with a curved portion receding from 325 the periphery inwardly toward the axis 330 of the rotor, a portion concentric with and 335 spaced from the casing rearwardly of the 340 said curved portion, a straight portion ex- 345 tends rearwardly from the concentric por- 350 tion, and curved portion extending from the 355 straight portion to the casing.

In testimony whereof, I affix my signa- 360

ture.

THOMAS R. PRINCE.
